TIE-ROD FOR CONCRETE CONSTRUCTION

Lerritt A. Reeves, Toronto, Ontario, Canada

Application March 30, 1931. Serial No. 526,515

3 Claims. (Cl. 25—131)

The principal objects of this invention are to provide a tie rod for clamping concrete forms in position which will be extremely reliable and efficient in use and very simple to manipulate both in setting up and removing the form and which will be readily adaptable to the construction of either straight or tapering forms and may be furnished at remarkably low cost.

The principal features of the invention consist 10 in the novel construction of a coupling sleeve for connecting the inner or buried rod with the outer or clamping member, whereby the sleeve and outer clamping members are simultaneously removed and a further feature consists in the 15 novel construction of the outer clamp with a swivel socket co-operating with a part spherical surface on the clamping arm.

In the accompanying drawing, Figure 1 is a cross sectional view through a form showing the 20 invention as applied to vertical and tapered wall surfaces.

Figure 2 is an enlarged part sectional elevational view of the device.

Figure 3 is a plan view of the outer clamp 25 bracket.

In the construction of concrete walls and abutments it is necessary to provide means for accurately and efficiently tying the opposing sides of the form in such a manner that the forms will 30 be held from buckling or getting out of line under the very heavy pressure to which they are subjected from the mass of poured concrete and it is desirable that the major portion of the tie shall be removed from the wall after the 35 concrete has set in the simplest possible manner and at the least expense, both in labour and material. The present invention accomplishes these desirable conditions in a very simple manner.

The central element of the tie rod consists of 40 a plain piece of steel rod 1 threaded for a short distance at each end.

Sleeve members 2, preferably formed of steel or cast iron, are threaded at one end to receive 45 the threaded end of the rod 1 and the perimeter 3 of this threaded end is tapered.

The outer and parallel end of the sleeve 2 is formed with a threaded orifice 4 which extends inwardly in a left hand thread which terminates 50 short of the inner end of the thread engaging the rod 1.

The tapered end of the sleeves, which are 55 threaded with a right hand thread, extend inwardly past the wall 6 of the mould and the tapered surface 3 readily releases from the con-

crete upon being rotated in a left-hand direction as will hereinafter appear.

A rod 7 provided with a left hand threaded end 8 is fitted into the threaded orifice 4 and the end thereof is preferably turned to engage the bottom 60 of the threaded orifice. The outer end of the rod 7 is provided with a right hand thread 9 which in order to provide for a greater speed in operation is preferably a long pitch square thread.

A cast metal plate 10, preferably rectangular in 65 form, is provided with a centrally arranged boss 11 in which is formed an elliptical orifice 12 which flares from the outer end of the boss inwardly to the flat face of the plate with the long axis of the ellipse arranged lengthwise of the 70 plate. The outward end of the orifice is bevelled to present a concaved edge which is engaged by the part spherical surface 15 of the wing nut 16 threaded on to the right threaded end 9 of the 75 rod 7.

The engagement of the spherical surface of the nut 16 with the bevelled recess allows the plate 10 to adjust itself to any required angle in accordance with the taper or batter of a wall or it will set in squared or perpendicular arrangement to the rod 7 without stress.

A hole 17 is bored through the outer end of the rod 7 for the insertion of a pin.

In assembling the form the centre rod, sleeves and outer rods may all be assembled and inserted through the orifices in the form. The plates 10 are then slipped over the ends of the rods 7 and are clamped tightly against the blocks 18 which are a part of or arranged against the form. It will be seen that the rods may be tightened 90 to hold the form securely in position by means of the nuts 16.

When the concrete has been poured and is set and the moulds or forms are to be removed, it is merely necessary to slip a pin, which may be an 95 ordinary nail, into the hole 17 and upon turning the nut 16 to the left it backs off from the bracket plate 10 until it engages the pin causing the rod 7 to be rotated in a left-hand direction. The rod 7 is of larger diameter than the rod 1 and upon 100 being turned to the left the end 7' thereof engages the shoulder 2' in the sleeve and rotates the sleeve therewith thereby effecting the unthreading of the right-hand threaded end of the sleeve from the rod 1 which is embedded in the concrete and 105 causing the sleeve to be withdrawn from its embedded position in the concrete. The smooth inner end of the sleeve being tapered, upon being rotated on the threaded rod instantly releases itself from the concrete without breaking or chip- 110

ping the concrete. The neat round holes left in the concrete by the tapered sleeve 2 may then be easily plugged in any desired manner.

It will be readily understood from this description that the parts are of extremely simple construction and they are rugged and durable and may be used indefinitely.

It is an important feature of this invention that when different diameters of centre rods are required it is merely necessary to change the sleeves 2 for others having a larger diameter of thread at the inner end as the outer threads are sufficiently heavy to handle any range of work, consequently only one set of plates, outer rods 10 and wing nuts will be required. Further, in the event of either coupling sleeves or outer rods being damaged the members may be separated and the damaged one replaced at the minimum cost or if the sleeves become clogged with cement 15 20 they may be removed and cleaned out.

What I claim as my invention is:

1. A tie rod, comprising a centre rod threaded with right hand threads, a tapered sleeve threaded on to said centre rod and having a left hand 25 threaded orifice in the outer end, an outer rod left hand threaded to fit the orifice of said sleeve, an annular shoulder formation on said sleeve between the respective left and right hand threaded portions thereof forming a stop to limit the inward 30 left hand threading movement of said outer rod whereby a continued left hand rotation of the latter effects the unthreading of said sleeve from the right hand threaded centre rod and the extraction of the sleeve from the concrete and 35 clamping means mounted on said outer rod.

2. A tie rod comprising a centre rod threaded at the end, a sleeve having a tapered end threaded on to the threaded end of said rod, a spirally threaded bore in the other end of said sleeve having the threads thereof leading in the reverse direction to the rod engaging thread of the other end, an outer rod spirally threaded into the spiral bore of said sleeve whereby on being rotated relative to the sleeve it may be displaced axially thereinto, means for positively limiting the inward axial displacement of the spirally threaded outer rod to positively interlock the same with the sleeve, whereby on continued rotation of said second mentioned rod to effect the unthreading of the sleeve from the first mentioned rod, and clamping means co-operating with the outer end of said outer rod.

80

3. A tie rod, comprising a centre rod threaded with right hand threads, a tapered sleeve threaded on to said centre rod and having a left hand threaded orifice in the outer end, an outer rod left threaded to fit the orifice of said sleeve and having a right thread at the outer end, stop means for definitely limiting the inward axial displacement of said outer rod in said sleeve 100 whereby a continued left hand rotation of said outer rod effects the unthreading of said sleeve from the right hand threaded centre rod and the extraction of the sleeve from the concrete, a nut threaded on the outer end of said outer rod, and 105 a clamping plate mounted on said outer rod to be engaged by said nut.
